UNITED STATES PATENT OFFICE.

ALFRED ARNOLD, OF TENAFLY, NEW JERSEY.

IMPROVEMENT IN DEVICES TO PREVENT BOILER-EXPLOSIONS.

Specification forming part of Letters Patent No. 55,801, dated June 26, 1866.

To all whom it may concern:

Be it known that I, ALFRED ARNOLD, of Tenafly, in the county of Bergen and State of New Jersey, have invented a new and useful Mode of Preventing Steam-Boiler Explosions; and I do hereby declare that the following is a full and exact description thereof.

Experimental science has developed two causes, either of which, under the requisite conditions, are capable of producing terrific explosions.

The first and popular theory is that relating to the spheroidal state of water when in contact with extremely hot metal, as when from low water the flues or other portion of the interior of the boiler become dry and unduly heated and are then flooded.

The second cause is the increased cohesion of the particles of water when purged of air, which, under the most favorable circumstances for such an event, admits its temperature to be raised more than 100° above the boiling-point at that pressure, and then ebullition necessarily commences with explosion. This second cause, though less familiar to the public than the first, appears to be more consistent with the conditions under which explosions usually occur.

My invention applies equally to either or both these theories, and to any and all others founded on the only rational hypothesis—namely, that explosions (not merely straining open of a weak boiler) occur from a degree of heat in some part of the boiler far above that due to the pressure therein.

The nature of my invention consists, first, in the employment of such thermometric devices as will give seasonable warning of danger whenever the water or that portion of the boiler to which they are applied becomes hotter than is due to the pressure, whereby the person in attendance may extinguish the fires or use such other means as he may think proper to prevent the catastrophe; and, second, in such a combination of devices as will give an alarm whenever the water or that portion of the boiler to which they are applied becomes hotter than is due to the pressure therein, but will disregard any variation in the temperature when accompanied with its corresponding pressure.

To enable others to use my invention, I will describe the devices and their operation.

Though my invention may be employed by the use of detached devices, such as a thermometric and pressure device or two thermometric devices so arranged that any variation in their several motions will produce a single resultant motion, I prefer the arrangement shown in the drawing, which is a longitudinal section of an instrument wherein all the requisites to illustrate and carry into operation the whole nature of my invention are combined in a simple and compact form.

A is a series of hollow elastic disks filled with water or other liquid whose boiling-point corresponds with that of water. If water is employed, it should be aerated or hold its full complement of air in suspension.

B is a small tube, one end open and the other closed. The lower or closed end is firmly attached to the exterior of A, and the upper or open end is closely fitted to but slides freely in a perforation in C. b b' are small perforations, which form communications from the exterior to the interior of B.

C is a screw-plug having a projection or boss on its upper surface, and is perforated at c. D D are connecting-rods firmly attached to the plug C and cross-head E. The latter is made fast to A.

This instrument should be applied through a perforation in the top of the boiler prepared to receive the thread of the plug C. The tube B and rods D D should be of sufficient length to carry A below the water-line, and so near that portion of the surface of the boiler or flue most likely to be unduly heated that it will be actuated at such times by the radiation or conduction of the metal. The exact locality of the instrument must depend on the kind of boiler to which it is applied, and will be determined by the user in accordance with these instructions.

Its operation is as follows: So long as the temperature in the boiler corresponds with the pressure the pressure in the instrument will exactly balance that in the boiler; but should the temperature of the water in the boiler exceed that due to the pressure, or should that portion of the surface of the boiler or flue in proximity to A be dry, and thus become unduly heated, then the pressure in A will exceed that in the boiler, and the elastic disks will yield to the internal pressure, forcing the end of B into C until b reaches the point c, when

steam from the boiler rushes through *b* into *B*, and through *b* and *c* into a steam-whistle, (not shown,) thus giving a constant alarm until the danger is averted.

What I claim as my invention, and desire to secure by Letters Patent, is—

1. The mode of preventing steam-boiler explosions, substantially as herein set forth.

2. The construction and arrangement of the devices necessary to carry the mode into operation, substantially as described.

ALFRED ARNOLD.
